BELT BUCKLE

Filed April 18, 1932

UNITED STATES PATENT OFFICE

DORSEY M. WIRTH, OF BUCYRUS, OHIO

BELT BUCKLE

Application filed April 18, 1932. Serial No. 605,918.

This application relates to expanding belt buckles, wherein the expanding member is a spring. The novel feature of this invention is to swingably connect the belt hole engaging tongue with the bight portion of the yoke of expanding belt buckles, as the following description of the drawing will show.

Figure 1 is a front view of one form of buckle contemplated by this invention.

10 Figure 2 is a longitudinal sectional view of Figure 1.

Figure 3 is a front view of another form of belt buckle included in this invention.

15 Figure 4 is a longitudinal sectional view of Figure 3.

Figure 5 is a front view of another form of belt buckle included in this invention.

Figure 6 is a front view of a fourth form of belt buckle included in this invention.

20 Figure 7 is a front sectional view of Figure 6.

Figure 8 is a front sectional view of Figure 1.

25 Figure 9 is a front view of another form of belt buckle included in this invention.

Referring to the drawing in detail. Common to the forms of Figures 1, 2, 3, 4, 5, 8, 9, is a belt connector.

30 This belt connector comprises a closed loop formed by bending a bar or wire into a U shape, the parallel legs of

35 this U shape are inserted thru the openings of the bight of each yoke member, as indicated in Figure 1 the legs are bent generally away from each other as at 43 and then bent again

40 inwardly as at 44, from which point they proceed directly into end abutting relation meeting at the point 45.

Common also to all the forms of the drawing is a U shape yoke member connected with

45 a buckle body. In Figures 1, 3, 6, the sides of this yoke member spread gradually outward from each other, its ends connecting with a buckle body. In Figure 5 the sides of

50 the yoke member extend parallel to each other, then outwardly as at 46, then upwardly as at 47, connecting with the buckle body 25.

55 In the forms of Figures 1, 3, 6, the yoke and buckle body can be formed from one single piece of bar or wire material. Ap-

proximately the center portion of the single piece of wire or bar would be taken as the buckle body, at the points 48 of Figure 1, the wire is bent downwardly, then inwardly so that the ends of the wire would be directly 55 into end abutting relation and form the bight portion of the yoke formation. Or any of the parts of the yoke member or buckle body may be either stamped from sheet material and formed into shape, or they may be cast. 60

Common to each form of buckle as represented in Figures 1, 2, 3, 4, 5, 8, 9, is a coil spring 4, carried on each of the belt connectors. The spring is disposed on each leg of the belt connector loops and continues 65 around the curved portion. The ends of the spring are adapted to abut the inner face of the bight portions. The spring supplies the resilient expanding character of the buckle.

Common to each form of the belt buckle in the drawing is a tongue member which is swingably mounted on or swingably connected with the bight portion of each style buckle, and which engages with the hole of a belt as a retaining means for the end of the 70 belt.

In Figure 1 the buckle body 1 is connected with the yoke member 40, the belt connector loop 3 is slidably mounted through openings in the bight portion of the yoke at points 41, 80 the coil spring 4 is carried by the belt connector 3 for longitudinal resistance between the yoke and belt connector. The belt hole engaging tongue 2 is centrally and pivotally connected with the bight portion of the yoke 85 and cooperates with the buckle body 1 in adjustably securing the belt end in the buckle.

Figure 2 is a longitudinal cross sectional view of Figure 1, showing how each leg of the belt connector 3 passes through an opening in the bight portion of the yoke 40 at the point 41.

Figure 3 is similar to buckle of Figure 1 except that it has a flanged bight 42, the buckle body 25 is connected with the yoke 40, 95 the belt connector 3 is slidably carried in openings of the bight, and the belt connector carries the coil spring 4, the tongue 2 is swingably carried on the flanged bight 100 portion.

Figure 4 is a cross sectional view of Figure 3, showing the yoke 40 with its flanged bight portion 42, 3 is the belt connector, 4 the coil spring and 25 the buckle body.

5 Figure 5 is a front elevational view of expanding belt buckle, having a yoke 40 connected with the buckle body 25, the yoke by means of openings in its bight portion carries the belt connector 3, the belt connector 10 carries the coil spring 4 for longitudinal resistance between the yoke and belt connector. The tongue 2 is swingably connected with the bight of the yoke 40.

Figures 6 and 7 disclose a modification of 15 the belt connector member 3 as shown in Figures 1, 3, 5, 8, 9. In the form as shown in Figures 6 and 7 the single bar 17 is slidably mounted in an opening in the bight portion of the yoke member 40 and a transverse 20 bar 11 is attached or formed on the connector to retain the end of a belt. A coiled spring 13 is disposed to have one end abut the bight portion of the yoke part, and the other end abut the disk or cross part 16, whereby a 25 resilient spring action similar to that as is obtained in the forms illustrated in Figures 1, 3, 5, 8, 9. The tongue member 12 by means of two eyed fingers 50, is swingably carried on the bight portion of the yoke as shown in 30 Figure 6.

Figure 8 shows the yoke and belt connector assembly that is described in Figures 1, 2, 3, 4, 5, 9, without the tongue member being attached. The belt connector 3 is shown slidably mounted through openings in the bight of the yoke 40, and the spring 4 carried on the belt connector.

In Figure 9 the construction of this form 40 of belt buckle is in common with the other forms shown in the drawing with the exception that the yoke part 20 is pivotally connected with the buckle body 31, the ends of the yoke member being eyed and pivoted to the arms 33 of the buckle body. The tongue member 2 is swingably carried on the bight portion of the yoke.

The belt connector 3 is carried slidably through openings in the bight portion of the yoke and the spring 4 is carried on the belt 50 connector as shown.

It is definitely understood that I do not desire to limit the application of this invention to the particular modifications set out herein to illustrate the principles thereof, and 55 any changes may be made in material and structure and arrangement of parts consistent with the spirit and scope of the invention.

What I claim:

1. A belt buckle of the type described comprising a belt connector assembly, a yoke having a flanged bight carrying the belt connector slidably in said bight, a spring on the belt connector for resisting longitudinal separation of the belt connector and the yoke, 60 a buckle body connected with the yoke, a belt 65

hole engaging tongue swingably carried on the flanged bight.

2. A belt buckle of the type described comprising a belt connector assembly, a yoke carrying the belt connector slidably in its bight, 70 a spring on the belt connector for resisting longitudinal separation of the belt connector and the yoke, a buckle body pivotally connected with the yoke, a belt hole engaging tongue swingably carried on the bight of the yoke. 75

3. A belt buckle of the type described comprising a belt connector assembly, a yoke carrying the belt connector slidably in its bight, 80 a spring on the belt connector for resisting longitudinal separation of the belt connector and the yoke, a buckle body connected with the yoke, a belt hole engaging tongue swingably connected with the bight of the yoke.

4. A belt buckle of the type described comprising a belt connector assembly, a buckle body having arms formed into yoke formation, said yoke carrying the belt connector slidably in its bight, a spring on the belt connector for resisting longitudinal separation of the belt connector and the yoke, a belt hole 90 engaging tongue swingably carried on the bight of the yoke.

In testimony whereof I affix my signature.
DORSEY M. WIRTH.
